(57) **CLAIM**

The ornamental design for a floor mounted cleaning accessory, as shown and described.

DESCRIPTION

FIG. 1 is a perspective view of a floor mounted cleaning accessory.

FIG. 2 is a side view of the floor mounted cleaning accessory.

FIG. 3 is a front view of the floor mounted cleaning accessory.

FIG. 4 is an opposite side view from FIG. 2 of the floor mounted cleaning accessory.

FIG. 5 is a back view of the floor mounted cleaning accessory.

FIG. 6 is a top view of the floor mounted cleaning accessory; and,

FIG. 7 is a bottom view of the floor mounted cleaning accessory.

The broken line showing is for illustrative purposes only and forms no part of the claimed design.
